UNITED STATES PATENT OFFICE.

CONRAD W. SAGER, OF PERRYSBURG, ASSIGNOR OF TWO-THIRDS OF HIS
RIGHT TO SAMUEL S. TERRY AND MILO R. SMITH, OF ROCHESTER, IND.

IMPROVEMENT IN BELT-FASTENERS.

Specification forming part of Letters Patent No. **222,535**, dated December 9, 1879; application filed October 18, 1879.

To all whom it may concern:

Be it known that I, CONRAD W. SAGER, of Perrysburg, in the county of Miami and State of Indiana, have invented a new and valuable Improvement in Belt-Fasteners; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a plan view of my improved belt coupling or fastener. Fig. 2 is a longitudinal section of the same, and Figs. 3 and 4 are perspective views of the parts of the coupling.

This invention has relation to improvements in fasteners for endless belts; and the nature of the invention consists in certain novel arrangements of the parts of a detachable fastener, as will be hereinafter more fully set forth.

In the annexed drawings, the letters A A' designate the parts of the fastener, which I will describe as follows: The part A is composed of the parallel cross-bars *a a'* and the depressed side bars *b b'*, converging slightly toward each other. The cross-bar *a* has projecting from its under side, partly across the interval between the cross-bars, a short lug, *c*, (the object of which will be hereinafter shown,) and the bar *a* is slightly beveled at its edge bounding said slot or interval, as shown at *i*. The part A' is also composed of two cross-bars, *e e'*, and two depressed side bars, *f f'*, that converge toward each other sufficiently to be easily passed between the corresponding bars of the part A, and each provided with a shoulder, *g*, upon its side, close to the bar *e* aforesaid. This bar is beveled upon its edge next the slot, as shown at *i'*, Fig. 2. The bar *e'* of part A projects a short distance beyond the side bar adjacent thereto, thus forming a lug, *l*.

The parts A A' of the coupling or fastener are interlocked as follows: The ends of the belts having been secured to the cross-bars *e a'*

in any suitable manner, the bar *e'* of part A' is introduced under the corresponding bar *a* of part A, the side bars of the former being received between those of the latter until it passes beyond the end of the lug *c*, the projecting end *l* of the cross-bar of the part A' being introduced into the slot of part A and passed over the side bar *b* of the latter. The sections of the coupling are then drawn away from each other until the lug *c* passes under the bar *e'* of part A', when the interlocking is complete. In this construction the side bars of the part A' are between those of part A; consequently there can be no endwise play. The ends of the side bars of section A abut against the shoulders *g* of the side bars of section A'; consequently there is no lengthwise play of said sections; and as the side bars of the said section are under the cross-bar of section A and the lug *c* of the cross-bar *a'* under the cross-bar, there can be no vertical displacement. The sections, however, readily adapt themselves to the convexity of the pulleys, owing to the edges of the bars *e' a* being beveled. Thus a complete reliable coupling is had, that may be easily disconnected, if desired, but cannot come apart casually.

What I claim as new, and desire to secure by Letters Patent, is—

The belt-fastening consisting of the section A, having the cross-bars *a a'*, converging depressed side bars *b b'*, and lug *c*, projecting from the under side of bar *a* toward bar *a'*, and the section A', having the cross-bars *e e'*, the depressed converging side bars *f f'*, having shoulders *g*, and adapted to be received between the side bars *b b'*, and the laterally-projecting lug *l* at one end of bar *e'*, the whole combined and operating as set forth.

In testimony that I claim the above I have hereunto subscribed my name in the presence of two witnesses.

CONRAD W. SAGER.
